SKELP BENDING MACHINE.

No. 353,808.

Patented Dec. 7, 1886.

UNITED STATES PATENT OFFICE.

JOHN H. PIERCE AND WILLIAM B. SANDFORD, BOTH OF KEWANEE, ILL.,
ASSIGNORS TO THE HAXTUN STEAM HEATER COMPANY, OF SAME PLACE.

SKELP-BENDING MACHINE.

SPECIFICATION forming part of Letters Patent No. 353,808, dated December 7, 1886.

Application filed August 6, 1886. Serial No. 210,240. (No model.)

To all whom it may concern:

Be it known that we, JOHN H. PIERCE and WILLIAM B. SANDFORD, citizens of the United States, residing at Kewanee, in the county of Henry and State of Illinois, have invented a new and useful Improvement in Skelp-Bending Machines, of which the following is a full description, reference being had to the accompanying drawings, in which—

10 Figure 1 is a plan. Fig. 2 is a front elevation. Fig. 3 is a side elevation. Fig. 4 is a cross-section at line *x* of Fig. 1. Fig. 5 is a detail, being a side elevation of the central guide.

15 The primary object of our invention is to provide a machine by the use of which skelp can be bent as the plates or sheets come from the rolls of a rolling-mill without reheating; and the leading features of our invention consist in providing a machine with a series of 20 rollers arranged in pairs, as shown and described, for the purpose of facilitating the bending of skelp, each pair of rollers differing in form from the others; in providing a central guide arranged between the several 25 pairs of rollers, and adapted to coact with the rollers in bending the skelp; in providing a weighted roller to aid in holding the skelp in position while it is being bent; in providing 30 improved devices for causing the tongs to grip automatically and hold the skelp while being drawn through the machine, and in certain combinations, all as illustrated in the drawings, and hereinafter described.

35 Those parts which we claim as new will be pointed out in the claims.

In the drawings, A represents the bed of the machine.

B B are two plates which rest upon the bed 40 A. These plates B B, as shown, have ribs on their under sides. They are so constructed and placed in position that they can be moved away from each other a little.

45 As shown in the drawings, a a are blocks upon each side of the machine, and C are screws which enter screw-threaded projections b upon the bed A. By means of these screws the plates B B can be firmly held together, and by loosening the screws the plates B B and the 50 rollers supported thereon can be moved away from each other a little.

c c' are two rollers, the form of which is shown in Fig. 3. These two rollers are pivoted upon posts which are secured, one in each of the plates B. *d d'* are another pair of rollers; *e e'*, a third pair of rollers; *f f'*, a fourth pair of rollers; *g g'*, a fifth pair of rollers, each pair differing from every other pair in form, and the form of each pair being clearly shown in the drawings.

h, Fig. 3, represents one of the posts which carries one of the rollers. Upon the top of each post there is a washer, and a pin passes through the washer and the post to firmly hold the roller in place. As shown in Fig. 3, the 65 post *h* has a slight enlargement near its lower end, and the roller is formed to correspond, thus furnishing a better bearing near the lower end of the roller.

D is a central guide resting upon the plates 70 B B, between the several pairs of rollers. It is secured in place by means of bolts *i*. The opposite vertical sides of this guide are formed, as indicated by dotted lines in Fig. 1 and by the shading in Fig. 5, for the purpose of lessening the friction of the skelp as it passes through the machine, and the upper edges of this guide D are cut away more or less to correspond with the form of the several pairs of rollers. This guide and the rollers are located 75 relatively to each other, so that there is sufficient space between them to permit the easy passage of the skelp. The forward end of this guide D is provided with arms, in which a roller, *j*, is pivoted. These arms and the roller 80 extend downward a little into a slot provided in the plates B, and the roller has a deep groove in its periphery, and there is a corresponding deep central groove, *k*, extending the whole length of the guide D, to permit the 85 passage of the tongs. At the front of the machine there is a guide-piece, E, forming an open mouth, into which the forward end of the skelp which is to be bent is first placed. This guide E is made in two parts, each of which is 90 secured to one of the plates B.

F is a chain, driven by a wheel, G, as usual.

H represents a pair of tongs. The upper half, *l*, is provided with a handle, *m*, at the rear end. The outer end of the lower half, *n*, 100 is grooved, as shown in Fig. 6, to receive the end of the upper half.

p is an arm or lever pivoted to the upper half, *t*, of the tongs. The lower end of this arm is slightly bent, and extends out so that it can enter the open links of the chain *F*.

5 *q* is a pin on the lower half, *n*, of the tongs. The action of the chain upon the arm *p* and its contact with the pin *q* causes the tongs to grip the skelp.

10 *I* is a skelp, which, as shown, has been partly drawn through the machine.

J J are two posts secured to the plates *B*, one on each side of the machine.

K is a rod pivoted in the upper ends of the posts *J*.

15 *L* is a lever, two parts of which, as shown, stand at about right angles to each other.

r is a roller carried by the lever *L*. *s* is a weight on the outer end of this lever.

The operation is as follows: The forward 20 end of the skelp to be bent is to be inserted in the mouth or guide *E*, the tongs having been first opened by hand and carried forward far enough to grasp the skelp. The tongs at this time will be in the groove *k* in the guide *D*.

25 The wheel *G* is to be driven in any suitable manner, and the movement of the chain will cause the tongs to grip the skelp through the action of the arm *p*, as before described, and, the chain continuing to move, the skelp will

30 be gradually drawn through the machine, and will be gradually bent to proper shape, it being first bent a little by passing between the first pair of rollers and the guide *D*, and being further bent as it is drawn between each

35 succeeding pair of rollers and guide, as indicated in Fig. 3. The roller *r*, during the operation, rests first upon the top of the tongs, and afterward upon the skelp, aiding to hold the same in position. The pressure of the

40 roller can be regulated by the position of the weight on the lever *L*.

If from any cause a skelp should become wedged in the machine, the two plates *B B* and the posts and rollers supported thereon can 45 be easily drawn away from each other, as before described, first loosening the screws *C* and the bolts *i*.

When the machine is used for bending skelps without reheating, it is of course to be located 50 so that the plates or sheets can conveniently pass from the rolls to the machine.

We find that by the use of this machine we are enabled to successfully bend skelp without reheating, which is a great saving.

55 We have not specifically described the forms of the rollers; but it will be observed that each succeeding pair is adapted to cause the skelp to be bent more than by the next preceding pair.

We have shown five pairs of these rollers; but 60 a greater or less number may be used, the form

being slightly changed as required by the change in the number. All of the rollers are concave, the form of the concavity of each pair being changed as shown in the drawings.

The plates *B B* may be secured to the bed 65 *A* by screws or bolts.

A stop is provided to limit the downward movement of the lever *L*.

What we claim as new, and desire to secure by Letters Patent, is—

1. In a machine for bending skelp, a series 70 of rollers arranged in pairs, each pair differing from the others in form, and adapted to act upon the skelp and cause it to bend while being drawn through the machine, in combination with a guide, *D*, arranged between the rollers, and provided with a groove, *k*, substantially as and for the purposes specified.

2. In a machine for bending skelp, a series 75 of rollers arranged in pairs, each pair differing from the others in form, and adapted to act upon the skelp and cause it to bend while being drawn through the machine, in combination with a guide, *D*, arranged between the rollers, and a grooved roller, *j*, pivoted at the 80 forward end of the guide *D*, substantially as and for the purposes specified.

3. In a machine for bending skelp, two adjustable plates, *B B*, each carrying a series of 85 rollers, formed substantially as shown, the rollers being arranged in pairs, in combination with a central grooved guide, *D*, substantially as and for the purposes specified.

4. In a machine for bending skelp, the guide *E*, made in two parts and supported on adjustable plates *B B*, in combination with a series of rollers arranged in pairs, and a guide, *D*, substantially as and for the purposes specified. 90

5. In a machine for bending skelp, a series 95 of rollers arranged in pairs, a central guide, *D*, provided with a groove, *k*, in combination with a pair of tongs, *H*, provided with a lever, *p*, substantially as and for the purposes specified.

6. In a machine for bending skelp, a series 100 of rollers of different forms arranged in pairs, and a guide, *D*, in combination with a pressure-roller, *r*, arranged over the guide, substantially as and for the purpose specified.

7. In a machine for bending skelp, a series 105 of rollers of different forms arranged in pairs, and a central guide, *D*, in combination with a weighted lever, *L*, carrying a pressure-roller, *r*, arranged over the guide *D*, substantially as and for the purposes specified.
